(57) **CLAIM**

The ornamental design for a blade for utility knife as shown and described.

DESCRIPTION

FIG. 1 is a top perspective view of a blade for utility knife showing the new design;

FIG. 2 is a right side view of the blade for utility knife, the left side view being a mirror image thereof;

FIG. 3 is an enlarged side view of detail 3 in FIG. 2 showing the configuration of the blade tip;

FIG. 4 is an enlarged front view of the blade for utility knife, the rear view being a mirror image thereof;

FIG. 5 is a top plan view of the blade for utility knife; and, FIG. 6 is a bottom plan view of the blade for utility knife. Broken lines in FIG. 3 depicting the enlarged view of detail 3 form no part of the claimed design.
